GAME BOARD

James A. Allen, 4966 College Ave.,
San Diego, Calif. 92115

Filed Apr. 9, 1969, Ser. No. 17,247

Term of patent 14 years

Int. Cl. D21—01

U.S. Cl. D34—5

Fig. 1

Fig. 2

Fig. 3

FIG. 1 is a perspective view of a game board showing my new design;

FIG. 2 is a side elevation view taken from the side opposite to that shown in FIG. 1; and

FIG. 3 is a sectional view taken on line 3—3 of FIG. 2.

I claim:

The ornamental design for a game board, as shown.
